UNITED STATES PATENT OFFICE.

EDGAR ROUSE SUTCLIFFE, OF LEIGH, ENGLAND.

MANUFACTURE OF TILES, ROOF-SHEETS, AND THE LIKE.

1,204,085

Specification of Letters Patent.

Patented Nov. 7, 1916.

No Drawing.

Application filed October 2, 1914. Serial No. 864,688.

To all whom it may concern:

Be it known that I, EDGAR ROUSE SUTCLIFFE, a subject of the King of Great Britain and Ireland, residing at Leigh, Lancashire, England, have invented certain new and useful Improvements in the Manufacture of Tiles, Roof-Sheets, and the like, of which the following is a specification.

- 10 This invention relates to the manufacture of tiles, roof sheets and the like and it has for its objects to manufacture such goods economically and to produce goods that are weather resisting and durable.
- 15 It is well known to produce artificial stone and like material from such substances as sand and lime which are formed into a pasty mass and molded under pressure and afterward subjected to treatment 20 with steam for hardening purposes. It has also been proposed to form slabs from molded masses of clay or other like substance mixed with asbestos and a binding material such as sodium silicate, by pressing 25 them while moist between metal plates in association with heating chambers through which steam is passed.

According to the invention slabs or sheets are formed from sand or like substances 30 and lime and are indurated while submitted to pressure.

The invention comprises the process as hereinafter described.

In carrying the invention into effect I 35 mix sand and lime in the proportion of 4 to 5 of sand to 1 of lime and I produce a liquid slip therewith. I mix with this slip, asbestos fiber beaten up previously into a pulp with water or otherwise, the quantity used being, for example, 15 per cent. reckoned on the finished weight. I then 40 press this liquid mixture in the molds of a suitable press. The mold is provided with a sacking or other suitable filter sheet and 45 either with or without a superposed paper sheet. The pressing operation is carried out with the purpose of expressing the water and leaving a slab or sheet fairly free from moisture. The pressed slabs or sheets are 50 then placed one upon the other while still on their filter sheet, a sheet being interposed of any suitable substance such as sheet iron or of previously hardened asbestos; and on a sufficient number of such sheets or slabs 55 being collected I press the pile and a further quantity of moisture may thereby

be expressed from the slabs or sheets. The slabs or sheets are then separated from the filter sheets and again piled one upon the other with sheets interposed of sheet iron 60 or other suitable material and again pressed so that thus the slabs or sheets are provided with smooth faces. I then clamp a number of such sheets or slabs together so as to retain them under pressure and I place the 65 sheets within a chamber where they may be subjected to the action of steam at a high or low pressure, so that they may be thus indurated in a manner similar to that usually employed in the production of lime 70 and sand bricks.

I advantageously use sand which is the refuse of glass polishing. This material is eminently suited for the purpose of the invention by reason of its fine condition, 75 but sand from any other suitable source may be used which may be specially prepared or ground for the purpose together with the lime. This operation may be carried out wet. I may, for example, use the 80 silicious waste from gold or other mines and I may even use blast furnace or other slags, or material such as pozzuolana found in Italy and elsewhere.

I claim:

1. A method of manufacture of tiles, roof sheets and the like from fine sand and lime, consisting in mixing the fine sand and lime together and producing a liquid slip, incorporating asbestos fiber with the said liquid 90 slip, compressing the liquid mixture within a mold for removing the main part of the water it contains, said mold being provided with filter cloths, removing the sheets or slabs thus produced, compressing the sheets 95 or slabs between the filter cloths for further reducing their content of water, and then indurating the slabs or sheets by their subjection to the action of steam and compression mechanically applied.

2. A method of manufacture of tiles, roof sheets and the like from fine sand and lime, consisting in mixing the fine sand and lime together and producing a liquid slip, incorporating asbestos fiber with the said liquid 105 slip, compressing the liquid mixture within a mold for removing the main part of the water it contains, said mold being provided with filter cloths, removing the sheets or slabs thus produced, compressing the sheets 110 or slabs between the filter cloths for further reducing their content of water, removing

the filter cloths, and then indurating the slabs or sheets by their subjection to the action of steam and compression mechanically applied.

- 5 3. A method of manufacture of tiles, roof sheets and the like from fine sand and lime, consisting in mixing the fine sand and lime together and producing a liquid slip, incorporating asbestos fiber with the said liquid 10 slip, compressing the liquid mixture within a mold for removing the main part of the water it contains, said mold being provided with filter cloths, removing the sheets or slabs thus produced, compressing the sheets 15 or slabs between the filter cloths for further reducing their content of water, removing the filter cloths, interposing metal sheets between the respective slabs, and indurating the said slabs by subjecting them to the 20 action of steam and to compression mechanically applied.

4. A method of manufacture of tiles, roof sheets and the like from fine sand and lime, consisting in mixing the fine sand and lime 25 together and producing a liquid slip, incorporating asbestos fiber with the said liquid slip, compressing the liquid mixture within a mold upon filter cloths for removing the main part of the water it contains, said mold 30 being provided with filter cloths, removing the sheets or slabs thus produced, compressing the sheets or slabs between the filter cloths for further reducing their content of water, and then indurating the slabs or sheets by their 35 subjection to the action of steam and compression mechanically applied.

5. A method of manufacture of tiles, roof

sheets and the like from fine sand and lime, consisting in mixing the fine sand and lime 40 together and producing a liquid slip, incorporating asbestos fiber with said liquid slip, compressing the liquid mixture within a mold for removing the main part of the water it contains, said mold being provided 45 with filter cloths, removing the sheets or slabs thus produced, compressing the sheets or slabs between the filter cloths for further reducing their content of water, removing the filter cloths and piling the said slabs one 50 upon the other with sheets of iron or other suitable hard material interposed, and then indurating the said slabs by subjecting them to the action of steam and to compression mechanically applied. 55

6. A method of manufacture of tiles, roof sheets and the like from fine sand and lime, consisting in mixing the fine sand and lime together and producing a liquid slip, incorporating asbestos fiber therewith, which fiber 60 is first beaten up into a pulp with water, compressing the liquid mixture within a mold for removing the main part of the water it contains, said mold being provided with filter cloths, removing the sheets or 65 slabs thus produced, compressing the sheets or slabs between the filter cloths for further reducing their content of water, and then indurating the slabs or sheets by their 70 subjection to the action of steam and compression mechanically applied.
